UNITED STATES PATENT OFFICE.

HENRY C. ZIMMER, OF PECOS, TEXAS, ASSIGNOR OF ONE-HALF TO ARTHUR LEE LIGON,
OF PECOS, TEXAS.

WAGON-TONGUE.

1,146,227.

Spécification of Letters Patent.

Patented July 13, 1915.

Application filed October 3, 1914. Serial No. 864,826.

To all whom it may concern:

Be it known that I, HENRY C. ZIMMER, a citizen of the United States of America, residing at Pecos, in the county of Reeves 5 and State of Texas, have invented certain new and useful Improvements in Wagon-Tongues, of which the following is a specification, reference being had therein to the accompanying drawings.

10 This invention relates to wagon tongues and has special reference to detachable tongues which are so formed as to be easily and efficiently secured to different sized hounds without regard to any particular 15 construction of wagon hounds to which the same are secured.

The principal object of this invention is the production of an adjustable wagon tongue which is provided with a plurality 20 of adjusting slides and a cog therefor, whereby upon the adjustment of the cogs the slides may be moved for increasing or diminishing the size of the adjusting portions of the tongue thereby allowing the 25 tongue to be easily secured to different sized hounds.

Another object of this invention is the production of a wagon tongue having adjustable portions whereby the simple rotation of the cog will increase or diminish the 30 size of the adjustable portions as the circumstances require at which time the adjustable portions may be tightened so as to be held in an adjusted set position for engaging 35 the wagon hounds, thereby allowing the tongue to be efficiently and easily secured in position.

With these and other objects in view this 40 invention consists of certain novel combinations, constructions, and arrangements of parts as will be hereinafter fully described and claimed.

In the accompanying drawings like characters of reference indicate like parts of the 45 several views wherein:—Figure 1 is a top plan view of the wagon tongue constructed in accordance with this invention, portions of the device being broken away. Fig. 2 is an assembled view of the wagon tongue 50 showing the same in side elevation; the pole thereof being broken away. Fig. 3 is a central longitudinal section through the adjusting portions of the wagon tongue. Fig. 4 is a bottom plan view of the supporting

frame for the pole and adjusting elements. 55 Fig. 5 is a section taken on the line 5—5 of Fig. 1 looking in the direction of the arrow. Fig. 6 is a section taken on the line 6—6 of Fig. 1. Fig. 7 is a section taken on the line 7—7 of Fig. 1. Fig. 8 is an enlarged 60 fragmentary section taken on the line 8—8 of Fig. 1 looking in the direction of the arrows. Fig. 9 is a section taken on the line 9—9 of Fig. 1. Fig. 10 is a fragmentary 65 top plan view of the adjusting portions of the wagon tongue showing the manner in which the slides are engaged by the adjusting cog. Fig. 11 is a detailed perspective view of one of the adjustable plates. Fig. 12 is a detailed perspective view of a certain 70 retaining link used in connection with this invention. Fig. 13 is a detailed perspective view of one of the adjusting slides. Fig. 14 is a detailed perspective view of the other 75 adjusting slide. Fig. 15 is a detailed perspective view of the adjusting cog. Fig. 16 is a fragmentary sectional view through a corner of the supporting frame illustrating the manner in which the adjustable plates 80 are slidably carried thereon. Fig. 17 is a 80 transverse section through one of the adjusting plates.

Referring to the accompanying drawings by numerals 1 designates the longitudinally extending angle bars which carry the transversely extending strip 2 adjacent their rear end and the transversely extending strip 3 adjacent their central portion, these strips 2 and 3 being held in fixed engagement with the angle bars 1 by means of the rivets 4 90 and 5. These transversely extending strips 2 and 3 carry at their outer ends the converging side angle bars 6. These bars are held upon the ends of the strips 2 and 3 by means of the retaining rivets 7. The strip 2 is also provided with angularly extending lips 8 which are secured to the rear end portions of the converging side bars 6 by means of the rivets 9. The forward end 95 of these side angle bars 6 is offset inwardly 100 as shown at 10 and extend to have their forward ends secured to the longitudinally extending angle bars 1 by means of the rivets 11. In forming the frame in this manner 105 it will be seen that the several portions efficiently reinforce each other and are held in engagement with each other by means of the rivets thereby forming a substantially

one-piece structure to which the pole and adjusting members are adapted to be detachably secured.

The pole 12 tapers as usual toward its forward end and has its rear end which is considerably larger than its forward end positioned between the longitudinally extending angle bars 1. In order to retain the pole in engagement with the supporting frame the bolts 13 pass through the forward ends of the longitudinally extending angle bars 1 while the bolts 14 extend through the rear end of the pole 12 and also through the opening 15 formed in the transverse strip 2. The bolt 16 also passes through the pole 12 and through the apertures 17 formed in the transverse strip 3. The upper end of this bolt 16 is provided with the sleeve 18 for purposes hereinafter to be set forth.

From the foregoing description it will be seen that the pole will be firmly held in engagement with the supporting frame so as to provide a rigid structure whereby the frame may be attached to the hound of the wagon so as to allow the pole to easily draw the wagon in any desired direction. In order to provide this frame with means for allowing the same to be easily adjusted according to the circumstances to fit different sized hounds, there is provided a simple and efficient means which may be adjusted and then held in a set position so as to form a rigid structure. This adjusting means comprises a pair of adjustable plates 19 and 20 which have integral lugs 21 extending therefrom adjacent their ends in which are formed longitudinal slots 22. These plates 19 and 20 are formed of an angle bar so as to constitute an L-shaped structure in cross-section whereby the plates may easily fit over the converging side angle bars 6 as is clearly shown in Figs. 5 and 7. The ends of the transverse strips 2 and 3 are provided with squared apertures 23 which register with the apertures 24 formed in the converging side bars 6. Retaining bolts 25 are passed through the apertures 23 and 24 and also through the slots 22 formed in the adjustable plates 19 and 20. It will be seen that by the operation of the adjusting members these plates may be moved outwardly or inwardly when the nuts 26 are loosened and then upon the tightening of these nuts 26 the plates will be firmly held in an adjusted set position to accommodate different sized hounds. The supporting plate 27 spans the distance between the longitudinally extending angle bars 1 and is fixedly secured in position thereon by means of the rivets 28 which pass through the angle bars 1 and the plate 27. The adjustable plates 19 and 20 are also provided with the integral posts 29 which posts pass through the openings 30 formed in the outer ends of the adjusting slides 31 and 32. These posts 29

are provided with transverse openings 33 through which the pins 34 are passed for retaining the adjusting slides 31 and 32 in engagement therewith and therefore upon the moving of these slides 31 and 32 the plates 19 and 20 will be adjusted to suit the circumstances. The angle bars 1 are also provided with squared apertures 35 registering with the apertures 36 formed in the plate 27 and through these apertures 35 and 36 there extend the retaining bolts 37. The adjusting slides 31 and 32 are also provided with longitudinally extending slots 38 and 39 which are positioned so as to allow the slots 38 to register as well as the slots 39. Since the outer end 40 of the adjusting slide 32 is offset and positioned below the plane in which the slide 32 extends, the slide 32 is allowed to overlap and rest upon the upper surface of the adjusting slide 31 as is clearly shown in Fig. 5.

It will be seen that after the slides 31 and 32 have been moved to adjust the plates 19 and 20 the nuts 41 may be tightened upon the bolts 37 so as to bind the washers 42 upon the outer surface of the adjusting slide 32 and in this manner positively retain the slides in an adjusted set position for assisting in holding the plates 19 and 20 in a set position. The adjusting slide 31 is provided with an enlarged longitudinally extending opening 43 while the adjusting slide 32 is provided with a similar opening 44. Each slide is provided with teeth 45 and 46 but it is to be noted that the teeth 45 of the adjusting slide 31 are formed upon the opposite side of the opening 43 to the teeth 46 extending in the opening 44 of the adjusting slide 32. When these slides are in position, however, it will be noted that the openings 43 and 44 will register so that the teeth 45 and 46 will extend inwardly toward the central portion of the openings. The plate 27 is provided with an opening 47 in which is journaled the bearing end 48 of the cog or gear wheel 49. This cog or gear wheel is positioned within the openings 43 and 44 so as to allow the teeth thereof to engage the teeth 45 and 46 of the adjusting slides 31 and 32. It will be seen that upon the rotation of this cog wheel 49 the teeth thereof will engage the teeth 45 and 46 of the adjusting slides thereby moving the slides to an extended position or moving the slides to a closed position, owing to the direction in which the cog wheel is rotated and thus the adjustable plates 19 and 20 will be quickly and efficiently adjusted to meet the circumstances. For the purpose of retaining these slides in engagement with the cog wheel 49 there is provided a link 50 having a U-shaped pocket portion 51 which fits over the cog wheel 49 and adjusting slides 31 and 32. This pocket portion 51 is provided with a round aperture 52 through which extends 130

the rounded portion 53 of the cog 49. It is to be noted, however, that this rounded portion 53 terminates in a squared outer end 54 which is adapted to be engaged by a wrench or any other suitable instrument for the purpose of rotating the cog 49 and adjusting the slides 31 and 32. The plate 27 is also provided with alined apertures 55 which register with the openings 56 formed in the link 50. Through these apertures 55 and openings 56 there extend the bolts 57 for retaining the link in engagement with the plate 27 thereby positively holding the adjusting slides 31 and 32 upon the plate 27 and in engagement with the cog or gear wheel 49.

The bolt 16 which passes upwardly through the pole 12 carries the sleeve 18 adjacent its upper end and is adapted to have the sleeve 18 pass through the strip 3 and also through the rear end of the bar 58. This sleeve 18 also passes through the openings 59 formed in the offset forward end 60 of the link 50. This offset forward end 60 is adapted to overlap the rear end of the bar 58 as clearly shown in Fig. 3 while the upper end of the bolt 16 carries the nut 61 thereby holding the bar 58 and forward end of the link 50 in engagement with the sleeve 18 and preventing the bolt from dropping from engagement with the sleeve and pole. The forward end of the bar 58 is adapted to carry the wrench or king pin 62 which passes downwardly through the opening 63 formed in the reinforcing plate 64 carried by the angle bars 1. This wrench 62 also passes downwardly through the pole 12 as is clearly shown in Fig. 3. The converging side angle bars 6 carry upon their under portions the brackets 65 which are positioned in alinement with the openings 66 formed in the pole 12. The converging side angle bars 6 and the adjustable plates 19 and 20 are also provided with registering openings 67 which also register with the openings formed in the brackets 65 and the openings 66 formed in the pole 12 and through these openings and brackets there extends the queen pin 68 having a nut 69. It will be noted that this queen pin 68 is used for attaching the tongue to the wagon hound.

When this device is in use it will normally assume the position disclosed in Fig. 1. If it is desired to attach the same to a hound of a particular size, the nuts upon the bolts 57 are loosened as well as the nuts 26 of the bolts 25. The nuts 41 are also loosened and then it will be seen that the adjustable elements may be easily removed. The wrench or other suitable instrument may grip the squared end 54 of the cog or gear wheel and then the gear wheel may be rotated in either direction. The gear wheel 45 and 46 of the ad-

justable slides 31 and 32 may move the plates 19 outwardly or inwardly until the plates have been moved far enough to fit snugly within the wagon hound at which time the queen pin 68 is secured in position. The nuts which have been previously loosened may again be tightened thereby forming a rigid structure which may easily draw a wagon without danger of losing its shape or collapsing. Furthermore, it will be noted that by the construction heretofore set forth that by the device may be easily adjusted without the removal of any of the bolts or parts.

From the foregoing description it will be seen that a simple adjustable tongue has been produced wherein the frame is formed to constitute a rigid construction for engaging a pole while the adjusting slides and adjustable plates may be easily moved and then held in a set position to accommodate different sized wagon hounds.

What I claim is:—

1. In a device of the class described the combination of a rigid frame, said frame adapted to carry a pole, adjustable plates carried by the side portions of said frame, adjusting slides secured to said plates, said slides overlapping each other, and a cog wheel engaging said slides for moving the same in a desired direction whereby said plates may be adjusted, and means engaging said slides for retaining said plates in an adjusted set position.

2. In a device of the class described the combination of a fixed frame, said frame adapted to carry a pole, adjustable plates slidably mounted upon the side portions of said frame, adjusting slides secured to said plates, said slides engaging and overlapping each other, said slides provided with enlarged longitudinally extending registering openings, said slides provided with teeth extending into said openings, a cog wheel rotatably supported by said frame and engaging the teeth of said adjusting slides, said cog wheel being adapted to be rotated for moving said slides whereby said adjustable plates may be moved in a desired direction and clamping bolts carried by said frame and passing through said slides for holding said slides in an adjusted set position after said adjustable plates have been moved.

3. In a device of the class described the combination of a rigid converging frame, adjustable plates slidably mounted upon the side portions of said frame, said plates being formed so as to constitute an L-shaped structure in cross-section to fit over the side portions of said frame, said plates provided with integral inwardly extending lugs, said lugs and said plates provided with longitudinally extending slots, retaining bolts carried by said frame and passing through said slots for assisting in holding said plates

in an adjusted set position, adjusting slides secured to said plates and engaging and overlapping each other, gear teeth formed upon said slides, a cog wheel carried by said frame and engaging said gear teeth, means for retaining said cog wheel in engagement with said gear teeth, said cog wheel being adapted to be rotated for moving said slides whereby said adjustable plates may be moved 10 and then held in an adjusted set position.

4. In a device of the class described the combination with a rigid frame, said frame adapted to carry a pole, adjustable plates slidably mounted upon the side portions of 15 said frame, adjusting slides secured to said plates and extending inwardly so as to engage and overlap each other, said slides provided with enlarged longitudinally extending openings registering with each other, 20 said slides provided with teeth extending

into said openings, a cog wheel supported by said frame and engaging said teeth, said cog wheel provided with a rounded portion, a link carried by said frame, said link provided with a U-shaped pocket, said pocket being adapted to fit over said cog and said slides and engage the rounded portion of 25 said cog, said cog being adapted to be rotated so as to move said slides whereby said plates may be moved, and said link being adapted to be tightened upon said frame whereby said cog will be held against rotation thereby holding said plates in an adjusted set position.

In testimony whereof I hereunto affix my 35 signature in presence of two witnesses.

HENRY C. ZIMMER.
